BRAKE ACTUATING SYSTEM

Glenn E. Edmunds, Columbus, Ohio, assignor to
The Bonney-Floyd Company, Columbus, Ohio,
a corporation of Ohio

Original application March 22, 1934, Serial No.
716,895. Divided and this application April 5,
1935, Serial No. 14,943

5 Claims. (Cl. 188—107)

The present invention relates to a brake actuating system for mine cars or the like, the system including hand levers mounted so that one is accessible from each side of the car and either 5 may be swung to apply the brakes. The present application is a division of my copending application Serial No. 716,895 filed March 22, 1934.

Practical embodiments of the invention are 10 shown by way of illustration in the accompanying drawings in which:

Figure 1 is an end elevation of a mine car showing a suitable form of brake mechanism manipulatable from either side of the car.

Figure 2 is a view similar to that of Figure 1 15 showing a modified form of brake actuating mechanism.

Figure 3 is a view similar to that of Figure 1 showing a further modified form of brake actuating mechanism, and

Figure 4 is a view similar to that of Figure 1 showing still further modifications.

Referring to the drawings and first to Figure 1, reference numeral 10 designates generally a mine car having a fixed end wall 11. Disposed at opposite sides on end wall 11 is a pair of hand levers 12 and 13, these levers being pivoted on bolts 14 and 15 for swinging movements in a plane parallel to the plane of the end wall. The upper ends of the hand levers are guided under straps 16 and 17 and are provided toward the wall with knife edges adapted to engage toothed segments 18 and 19 whereby the levers may be held in adjusted position. Common releasing means for the hand levers is provided by cam portions 20 and 21 formed on a rod 22 journaled between the levers and the car end wall in brackets 23, 24, and 25, the ends of the rod being provided with arms 26 and 27, either one of which may be grasped to rock the rod and so cam the upper ends of the levers out of engagement with their segments to permit them to return to inoperative position.

Pivoted to the car end beneath hand lever 12 on a bolt 28 is a three-armed bell crank lever having a substantially horizontally extending arm 29 and upwardly and downwardly extending arms 30 and 31. Arm 30 is connected to the lower end of hand lever 12 by means of a link 32. Arm 29 has connected thereto one end of a link 33 whose other end engages the substantially horizontally extending arm 34 of a bell crank lever whose other downwardly extending arm 35 is in operative connection with the brakes on that side of the car. The bell crank lever 34, 35 is pivoted 50 to the car structure on an axis extending trans-

versely of the latter. Such a lever and its manner of connection to the brakes is shown in my application above mentioned, and since this lever and the transmission means therebeyond are without importance so far as the present invention is concerned, their description here is thought to be unnecessary.

A three-armed lever pivoted on a bolt 36 beneath hand lever 13 has a substantially horizontally extending arm 37 and upwardly and 10 downwardly extending arms 38 and 39. Arm 38 is connected with the lower end of hand lever 13 by means of a link 40 and arm 37 is connected by means of a link 41 with one arm of a bell-crank lever 42 similar in all respects to the lever 34, 35, but connected with the brakes on the opposite side of the car. Arm 31 is connected by means of a link 43 with arm 38, and arm 30 is connected by means of a link 44 with arm 39. Thus as regards the three-armed levers it will 20 be noted that their horizontally extending arms project in opposite directions and that the upper arm of one is connected to the lower arm of the other, while the lower arm of the first is connected with the upper arm of the second. 25

If the brakes are to be applied, the upper end of lever 12, for example, is swung toward its side of the car so that the associated three-armed lever is swung in a clockwise direction. At the same time the other three-armed lever has been 30 swung in a counter-clockwise direction through link 43, the consequent upward movement of arms 29 and 37 rocking the lower bell crank levers and applying the brakes at both sides of the car. To release the brakes the knock-off cam is operated so that both the hand levers are free from 35 their segments and may be returned. All of the described linkage is rigid and thus effective under compression as well as under tension, so that the brakes may be positively released. It should also be mentioned that links 43 and 44 are of equal 40 length and are pivoted to the associated arms of the three-armed levers at equal distances from the axes of the levers. In view of the provision of the two links 43 and 44, one acts under tension 45 no matter which of the hand levers is moved to apply the brakes. It is preferable that the brake actuating linkage, particularly where the parts are of any considerable length, act under tension 50 for brake actuation as will be appreciated.

The arrangement shown in Figure 4 is similar to that shown in Figure 1 with the exception that the three-armed levers 45 and 46 have their horizontally extending arms projecting inwardly and 55

the hand levers 47 and 48 are formed integral with the three-armed levers respectively. The arrangement functions exactly as that above described.

- 5 In the arrangement shown in Figure 2, the three-armed levers 49 and 50 are arranged substantially as in Figure 1. In this instance, however, the hand levers 51 and 52 have pin and slot connections with the three-armed levers, 10 the pins and slots being designated at 53, 54, 55, and 56 respectively. The slot 54 is formed in a link 57 provided at its other end with a plurality of apertures through any one of which the link may be pivotally engaged through a pin 58 with 15 a hand lever 51. The slot 56 is formed in a similar link 59. With this arrangement, hand lever 51, for example, may be swung outwardly to apply the brakes without affecting the position of hand lever 52, pin 55 merely moving to 20 the right in slot 56. Similarly the brakes may be applied by hand lever 52 without affecting the position of hand lever 51. However, a knock-off 25 cam 60 may be provided, if desired, for use particularly when the pin and slot connections provide insufficient lost motion due to uncorrected stretching of the linkage or wear of the brakes so that when one hand lever is actuating the other may be moved to some extent along its cooperating segment. Due to the provision of 30 the slots positive release of the brakes is not possible so that spring release means are provided. As here shown, the lower bell-crank levers 61 and 62 which correspond to those described with reference in Figure 1 may have their 35 lower arms engaged by tension springs 63 and 64 whose other ends are suitably anchored to fixed parts of the car. Springs 63 and 64 act to release the brakes and hold them released.

In Figure 3 a single three-armed lever 65 is 40 provided. The horizontally extending arm of this lever has a link 66 suspended therefrom and pivotally supporting at its lower end an equalizing bar 67. Link 66 lies substantially in the central vertical longitudinal plane of the car and 45 engages the central portion of the equalizing bar. To the ends of the bar 67 are connected links 68 and 69 whose other lower ends engage bell-crank levers 70 and 71 exactly the same as levers 61 and 62 of Figure 2 and similarly spring-influenced, 50 the springs being designated at 72 and 73. A hand lever 74 has a pin and slot connection with one end of a link 75 whose other end is pivoted to the lower arm of lever 65, the upper end of 55 the latter being connected by means of a link 76 with a hand lever 77 and having a pin and slot connection with the same. Here, as in the construction shown in Figure 2, either hand lever may be manipulated without affecting the position of the other, the equalizing bar functioning 60 in the well-known manner.

It will be evident that while I have mentioned a pair of hand levers as being a desirable provision in the various elements just described, one lever might be omitted in each instance without affecting the operability of the system.

Furthermore, in the embodiment of Figure 1, for example, one of the links 43, 44 might be omitted, but in this case, the remaining link

would be a compression member upon actuation of one of the hand levers and a tension member upon actuation of the other. The invention is susceptible of varied embodiment and accordingly I do not limit myself as regards the specific form and arrangement of elements above described, the scope of the invention being defined in the following claims.

I claim:

1. The combination with a wheeled car, of brake 10 operating mechanism comprising a pair of three-armed levers pivoted on one end of the car, each of said levers comprising a substantially horizontally extending arm and substantially upwardly and downwardly extending arms, transmission members in operative connection with said horizontally extending arms, a pair of links connecting the other arms of said levers, and a pair of hand levers of which one is arranged at each side of the car end in operative association 15 with one of said three-armed levers, the arrangement being such that swinging of either of said hand levers causes rocking of both of said three-armed levers and consequent operation of said transmission members, the three-armed levers 20 being positively operable by the hand levers in either direction of movement of the latter and the transmission members being effective both under tension and compression.

2. The combination with a wheeled car, of 30 brake operating mechanism comprising a pair of hand levers of which one is arranged at each side of the car at one end of the latter, a pivoted three-armed lever at the same end of the car, 35 said lever having a substantially horizontally extending arm and substantially upwardly and downwardly extending arms, an equalizing bar suspended centrally from said horizontally extending arm, transmission means connected to the outer ends of said bar, and links connecting 40 said hand levers with the upper and lower arms of said three-armed lever respectively.

3. Apparatus according to claim 2 wherein the hand levers are associated with the three-armed lever through pin and slot connections so that 45 one of said hand levers may be operatively moved without affecting the position of the other hand lever and wherein spring means are provided for returning the transmission members.

4. The combination with a wheeled car, of 50 brake operating means comprising a pair of hand levers of which one is arranged at each side of the car at one end of the latter, toothed segments associated with the hand levers for holding 55 them in adjusted position, and knock-off cams for the levers operable from either side of the car.

5. The combination with a wheeled car, of 60 brake operating means comprising a pair of hand levers of which one is arranged at each side of the car at one end of the latter, toothed segments associated with the levers for holding them in adjusted position, and a rod extending from side to side of the car at the said end of the latter and having rigid therewith knock-off cams for 65 the levers, said rod being manually rockable from either side of the car.

GLENN E. EDMUNDSEN.
